UNITED STATES PATENT OFFICE.

JOHN HAYS HAMMOND, JR., OF GLOUCESTER, MASSACHUSETTS.

PEDAL CONTROL OF STOP ACTIONS.

Application filed August 22, 1922, Serial No. 583,605. Renewed February 15, 1927.

This invention relates to the control of organs and the like, and more particularly to the manual or pedal control of stop actions thereof.

5 Some of the objects of the present invention are to provide for controlling such stop actions by means convenient to the organist's position or "manual"; to provide for selectively connecting a desired group 10 of stops to the pedal or other device which controls the swell shutters to which the selected group of stops belongs; to provide for the successive actuation of desired groups 15 of stops at the same time that the swell shutters are opened; to provide for performing 20 both of these functions when a single operating device is displaced; and to provide other objects as will appear from the following description taken in connection with the accompanying drawings, in which

Figure 1 shows diagrammatically so much of a pipe organ, and the electrical connections therefor, as is necessary to an understanding of the invention; Fig. 2 shows a 25 side elevation of a portion of the mechanism of Figure 1; and Figure 3 is a detail view of one of the tablets of Figure 1.

Referring to Figure 1 the mechanism shown comprises two organs 11 and 12 which 30 are respectively contained in two swell chests 13 and 14, the shutters of which are controlled by swell motors 15 and 16; a bank of tablets 18 for controlling the stop actions of the two organs; and pedal action 20 and three groups of switching means such as relays 21, 22, and 23.

The organ 11 is composed of a group 40 of eight stops 31 to 38 inclusive and the organ 12 is composed of six stops 41 to 46 inclusive. The stops 31 to 38 of the organ 11 are connected by conductors 51 to 58 inclusive respectively to a corresponding plurality of contacts such as 59 (see Figure 3) located rearwardly of tablets 61 to 68 inclusive. Similarly, stops 41 to 46 of the organ 45 12 are connected by conductors 71 to 76 to contacts such as 59 located rearwardly of the tablets 81 to 86 inclusive. The tablets are pivotally mounted upon a rod 87 which 50 is connected by a conductor 88 to a battery 89. The lower side of each of the tablets is provided with a similar metallic strip such as 95 which always makes electrical

contact with the rod 87 and when the associated tablet is operated contacts with the 55 respective contact 59.

The swell chests 13 and 14 are provided with sets of shutters 90 and 91 respectively which are pivotally mounted in an opening in one face of the respective swell chest. 60 Each group of shutters is connected together by means of rods 98 and 99 which are pivoted to the shutters and which are connected by means of links 101 and 102 to the swell motors 15 and 16 respectively. The swell 65 motor 15 is connected by conductors 104 to 108 inclusive to contacts 110 to 114 inclusive. These contacts are rigidly mounted upon the frame work 116. The swell motor 16 is connected by wires 118 to 122 inclusive to the contacts 125 to 129 inclusive, which are rigidly mounted upon the framework 116. A common return conductor 130 extends from the swell motors 15 and 16 and from the stop actions of the organs 11 and 70 12 to the battery 89. Slidably mounted in the framework 116 are two square rods 131 and 132 made of any suitable insulating material and upon their upper ends are mounted two plates 133 and 134 of conducting 75 material. Rigidly mounted upon the framework 116 and normally in contact with the conducting strips 133 and 134 are two contacts such as 135 which are connected to the conductor 88. The rods 131 and 132 80 are connected by links 137 and 138 to pedals 139 and 140 which are loosely mounted upon a transverse rod 141. Rigidly mounted upon the framework 116 are three contacts 145, 146 and 147 which are connected by 85 conductors 148, 149 and 150 to three contact springs 151, 152 and 153 of the relay 21. One terminal of the winding of the relay 21 is connected to the contact of a tablet 164 such as previously described. The 90 other terminal of the winding is connected to the common return conductor 130 and thus to the battery 89. The contacts cooperating with contact springs 151, 152, 153 are connected to conductors corresponding 100 to desired stops, such as conductors 55, 53 and 57 respectively.

In parallel with the contact springs 151, 152 and 153 of the relay 21 are connected contact springs 184, 185 and 186 of the relay 105 22, the contacts cooperating with which are

connected to conductors corresponding to desired stops, such as conductors 51, 58 and 54, respectively. One terminal of the winding of the relay 22 is connected by way of the common return conductor 130 to the battery 89, and the other terminal is connected to a contact of a tablet 200.

Affixed to the framework 116 opposite the contacts 145, 146, 147 are similar contacts 211, 212 and 213, connected by means of conductors 214, 215 and 216 to contact springs of the relay 23. The contacts co-operating with these contact springs are connected to conductors corresponding to desired stops of the organ 12, such as conductors 72, 74 and 75 respectively. One terminal of the winding of the relay 23 is connected by way of the common return conductor 130 to the battery 89 and the other terminal thereof is connected to the contact of a tablet 230.

In the operation of the form of this invention shown in Figures 1, 2 and 3 the stops of the organ 11 are controlled by depressing the upper ends of the tablets 61 to 68, which when they are depressed, close the circuits through the conductors 51 to 58 and thereby energize the stop action of the stops 31 to 38. The stops of the organ 12 are controlled in a similar manner by tablets 81 to 86. The shutters 90 of the organ 11 are operated by the swell motor 15, the action of which is controlled from the pedal 139, which when its upper end is depressed causes the rod 131 to move down, thus bringing the plate 133 successively into engagement with the contacts 114 to 110; thus successively closing the circuits through the wires 108 to 104; which causes the swell motor 15 to move by steps, and opening the shutters 90 in a step by step manner. The shutters 91 of the organ 12 are controlled by the swell motor 16, which in turn is operated by the pedal 140 in a manner similar to that just described for the organ 11.

When it is desired to control the group of stops 55, 53 and 57 by means of pedal 139, the tablet 164 is depressed, which closes the circuit through the winding of the relay 21, thus operating the relay. This causes the contacts of the relay to close. When the pedal 139 is depressed to operate the shutters 90, the contacts 145, 146 and 147 are successively engaged by the strip 133, thus closing the circuits through the stops 55, 53 and 57 in succession.

In a similar manner the stops 51, 58 and 54 are controlled from the pedal 139 by depressing the tablet 200, which operates the relay 22 as described for relay 21.

If it is desired to control the stops 42, 44 and 45 of the organ 12 from the pedal 140, the tablet 230 is depressed. This causes the operation of the relay 23 and these stops are connected to the contacts 211, 212 and 213

so that when the pedal 140 is depressed the conducting strip 134 successively engages these contacts, thereby energizing the stop action of the stops 42, 44 and 45.

It is evident from the foregoing description that when suitable tablets are depressed certain groups of stops of an organ will be successively thrown into action at the same time that the swell shutters of the organ are opened, both of these functions being simultaneously controlled from the same pedal.

What is claimed is:—

1. In a musical instrument actuated by a fluid agent, a plurality of stops, means for controlling a desired number of said stops, a swell shutter for controlling the passage of fluid agent therethrough, and means including a pedal and an electro-magnetic relay operatively interconnecting said pedal with at least some of said stops for simultaneously controlling a predetermined number of the stops and opening the swell shutter a proportional amount.

2. In a musical instrument actuated by compressed air, a plurality of stops, means for controlling a desired number of said stops, a swell shutter for controlling the passage of air therethrough, and means including a pedal and an electro-magnetic relay operatively interconnecting said pedal with at least some of said stops for simultaneously controlling a predetermined number of the stops and opening the swell shutter a proportional amount.

3. An organ comprising stops, a swell shutter, and means including a pedal and an electro-magnetic relay operatively interconnecting said pedal with at least some of said stops for throwing into operation a predetermined number of stops and opening the swell shutter a proportional amount.

4. An organ comprising stops, a tablet for controlling each of the stops, a swell shutter, a motor for operating the shutter, a pedal for controlling the shutter, control means including an electro-magnetic relay for operatively interconnecting a predetermined number of the stops and said pedal, and a tablet for controlling the operation of said control means.

5. In a musical instrument operated by a fluid agent, the combination with a plurality of stops, means for controlling a desired number of said stops, means for transmitting thereto a fluid agent for actuating selected ones of said stops, a swell shutter for controlling the volume of sound effectively produced by the instrument, a motor for operating the shutter, a pedal for controlling said motor and control means including an electro-magnetic relay for modifying the action of said pedal with respect to certain of said stops.

6. In a musical instrument, the combination with a plurality of means for producing

sound, a plurality of control devices for controlling the action of said sound producing means, means for variably controlling the volume of sound emitted, an electro magnetic relay for changing the sequence of operation of said sound producing elements and means for rendering said relay effective at the will of an operator.

7. In a musical instrument actuated by a fluid agent, a plurality of stops, a swell control mechanism, and means operable by a single control for varying said swell control mechanism and simultaneously operating successively a plurality of pre-selected stops, whereby the volume of the produced music may be varied at a uniform rate.

8. In a musical instrument actuated by a fluid agent, a plurality of stops, a swell control mechanism, foot operated means for pre-selecting a sequence of stops and single means for varying said swell control mechanism and simultaneously operating said pre-selected sequence of stops, whereby the volume of the produced music may be varied at a uniform rate.

9. In an organ operated by compressed air, a plurality of stops, a swell control mecha-

nism, a foot operated pedal for pre-selecting a sequence of stops, and a second foot operated pedal adapted to simultaneously vary 30 said swell control mechanism and operate in sequence said pre-selected stops.

10. In an organ adapted to be operated by compressed air, a plurality of stops, and a swell control mechanism, a relay for controlling a pre-selected set of stops in a pre-determined sequence, a foot operated pedal for simultaneously operating said relay and varying said swell control mechanism.

11. In an organ adapted to be operated by fluid pressure, a plurality of stops, and a swell control mechanism, a plurality of relays, each of said relays being adapted to operate a pre-selected sequence of stops, an individual foot operated pedal for each of 45 said relays and a master control pedal, said individual pedals being adapted to selectively connect said relays to said master pedal, said master pedal being adapted to simultaneously vary said swell control mechanism and to operate the pre-connected relay.

In testimony whereof I hereunto affix my signature.
